US00D915290S

(12) **United States Design Patent** (10) **Patent No.:** **US D915,290 S**
Ghasabi (45) **Date of Patent:** **** Apr. 6, 2021**

(54) **CONNECTOR FOR A LIGHT FIXTURE SYSTEM**

(71) Applicant: **Luminiz Inc.**, Etobicoke (CA)

(72) Inventor: **Amir Ghasabi**, Etobicoke (CA)

(73) Assignee: **Luminiz Inc.**, Etobicoke (CA)

(**) Term: **15 Years**

(21) Appl. No.: **29/702,695**

(22) Filed: **Aug. 21, 2019**

Related U.S. Application Data

(62) Division of application No. 29/650,879, filed on Jun. 11, 2018, now Pat. No. Des. 875,997.

(57) **CLAIM**

The ornamental design for a connector for a light fixture system, as shown and described.

DESCRIPTION

FIG. 1 shows a top perspective view of a connector for a light fixture system of my design;

FIG. 2 shows a bottom perspective view thereof;

FIG. 3 shows a left side elevation view thereof;

FIG. 4 shows a front side elevation view thereof;

FIG. 5 shows a right side elevation view thereof;

FIG. 6 shows a top plan view of the design thereof; and,

FIG. 7 shows a bottom plan view thereof.

The broken line portions are included to show unclaimed subject matter only and form no part of the claimed design.

1 Claim, 3 Drawing Sheets
